UNITED STATES PATENT OFFICE.

RALPH EARLY DUFFY, OF CLINTON, MISSOURI.

INSULATOR SUPPORT.

Application filed December 20, 1923. Serial No. 681,836.

To all whom it may concern:

Be it known that I, RALPH E. DUFFY, a citizen of the United States, residing at Clinton, in the county of Henry and State 5 of Missouri, have invented a new and useful Insulator Support, of which the following is a specification.

This invention relates to metallic insulator supports adapted to be used at the 10 tops of poles in place of the usual cross arms.

Some of the principal objects of the present invention are to provide a metal arm, or a series of arms, for this purpose arranged 15 in such a manner that the greatest resistance is offered to strains caused by the weight of the conductor, and a large and ample bearing surface is brought into contact with the pole; to provide a metal arm 20 in which no part of the metal is brought near the conductor to make a short path for the current to jump to the ground, and also making it practically impossible for squirrels, birds or the like to form a path between 25 the conductor and the ground; to provide means for securely clamping a wooden insulator pin having a large base without causing undue decay of the wood at the point of attachment to the clamp; and 30 to provide a metallic arm for clamping a wooden pin, and at the same time increasing the distance between the conductor and the metal of the cross arm and eliminating the metal from the inside of the insulator, 35 thereby greatly reducing the dielectric tension upon the insulator.

The objects and advantages of the invention will be better understood from the following detailed description taken in connection 40 with the accompanying drawings, in which,

Figure 1 is a front elevation of the invention applied to the upper end of a pole.

Figure 2 is a side elevation thereof.

Figure 3 is a plan view thereof.

Figure 4 is a detail sectional view taken on the line 4-4 of Figure 1.

Figure 5 is a detail view of one of the insulator pins.

Figure 6 is a perspective view of one of the metallic elements forming a part of the invention.

Figure 7 is a front elevation of a modified form of the invention.

As illustrated in the drawings, the invention includes a pair of similar metallic

members 10 and 11, which are adapted to be secured to the upper end of the pole at opposite sides thereof by bolts 13, or the like. These members may be in the form of channel bars, or they may have a circular cross section, or may be in any other form adapted for the purpose. As shown in Figure 1, the upper ends of the members 10 and 11 are bent inwardly above the top of the pole 12, as indicated at 14, and are adapted to receive between them a wooden insulator pin 15, which may be secured by a bolt 9. The lower ends of the members 10 and 11 are bent outwardly and upwardly, 65 terminating in vertical portions 16, which are spaced a suitable distance from the pole, and also extend upwardly a considerable distance above the lower parts 17 of the metallic members. The terminal clamping 70 portions 16 are adapted to cooperate with the vertical upper end clamping portions 18 of outer metallic bars or members 19 and 20 to receive insulator pins 15, which may be secured by bolts 21. The bars 19 and 80 20 slope downwardly toward the pole 12, and terminate in vertical portions 22, engaging opposite sides of the pole, and secured thereto by one or more bolts 23.

In the adaptation of the invention, as shown in Figure 7, a pair of members 24 and 25, similar to the members 10 and 11, are secured in a similar manner to the upper ends of members 26 and 27 to receive insulator pins, in the same manner as shown in Figure 1. The lower ends of the members 26 and 27, however, instead of terminating in vertical portions which are secured to the pole, are continued to form outwardly and upwardly bent terminal portions 28, which cooperate with the upper ends of similar members 29 and 30. The lower ends of the last named members may also be continued to form outwardly and upwardly bent terminal portions 31, which cooperate with the lowermost members 32 and 33, the latter being similar to the members 19 and 20 of Figure 1. Thus, it will be seen that the members 26, 27, 29 and 30 are shaped so as to form at their upper ends the outer securing member for corresponding insulator pins, while their lower ends form the inner securing members for other insulator pins. As many pairs of these intermediate members may be used as is necessary for the number of conductors which are to be carried by the pole.

The outer clamping members, as for example, the members 19 and 20 in Figure 1, slope downwardly and inwardly from the outer side of the insulator pin in a direction which is best adapted to resist the strains caused by the weight of the conductor. Outward, as well as downward movement of the insulator pin, is also resisted by the cooperating inner clamping members. The latter are also so shaped that the portion 17 extending between the pin and the pole is at a considerable distance from the insulator, so as to prevent the current from jumping across the gap and also to prevent squirrels, birds or the like from bridging or partially bridging the gap, and thereby forming a path for the current between the insulator and ground. The formation of the several pin supporting members in separate parts connected by a bolt passing through the pin, makes it possible to use a pin of larger size, and consequently stronger, without unduly increasing the size of the support. Another advantage of the invention is that where only one conductor is desired at first, it is only necessary to use the members 11 and 20. If it is desired later to add another conductor, the members 10 and 19 may be quickly attached merely by removing the nuts from the bolts 13 and 23, respectively. This can be done without interrupting the electric service on the first circuit. It will also be noted that any number of circuits may be attached to the pole, using a minimum number of standardized parts. Likewise in the form shown in Figure 7, a single three wire circuit may first be supported by the members 25, 27, 30 and 33 and other suitable parts, and later by removing the nuts from bolts 13 and 23 similar members 24, 26, 29 and 32 may be added to support another circuit.

The top pin 15, as shown in Figures 1 and 7, may be used to carry a ground wire or grounded conductor for protection against lightning, and this pin may be made of metal instead of wood.

It will be readily seen that various other modifications may be made in the size or shape of the several parts of the supporting devices, or in the manner in which they are arranged without departing from the salient features of the invention. It is my desire, therefore, to include all such modifications as may fall within the scope of the appended claims.

What is claimed is:

1. An insulator support, comprising a metallic bar securable to a pole and having a terminal portion spaced from and parallel to the pole to which the bar is secured and engageable with the inner vertical face of an upright insulator pin, a second metallic bar securable to said pole and having a terminal portion engageable with the outer

vertical face of said pin, and means for securing said terminal portions in supporting relation to said pin.

2. An insulator support, comprising a metallic bar securable to a pole and terminating in a U-shaped bend, the outer leg of which is directed vertically upwardly and spaced from the pole engaging portion and engageable with the inner vertical face of an upright insulator pin, a second metallic bar securable to said pole at a point below the first bar and having a terminal portion engageable with the outer face of said pin, and means for securing the pin between said terminal portions. 70

3. An insulator support, comprising a metallic bar having a portion securable in vertical position in engagement with a pole, and having a terminal portion spaced from and parallel to the pole engaging portion and engageable with the inner vertical face of an upright insulator pin; a second metallic bar securable to said pole and having a portion inclined upwardly and outwardly from the point of engagement with the pole, and terminating in a vertically upwardly extending portion engageable with the outer vertical face of said pin. 80

4. An insulator support, comprising a metallic bar having a straight portion provided with means for securing it in vertical position in engagement with a pole and terminating at its lower end in a U-shaped bend, the outer end of which is directed vertically upwardly and spaced from the pole engaging portion and engageable with the inner vertical face of an upright insulator pin, a second metallic bar having a portion adapted to be secured in vertical position below the first bar and in engagement with said pole, and having its upper end continued upwardly and outwardly from the point of engagement with the pole and terminating in a vertical upwardly extending portion engageable with the outer face of said pin, and means for clamping said pin between the terminal portions of said bars. 95

5. A metallic insulator supporting bar, comprising an intermediate straight portion provided with means for securing it in vertical position in engagement with a pole, the upper end of said bar continuing in an upwardly and outwardly inclined direction from the pole engaging portion and terminating in a vertical upwardly extending portion adapted to be clamped against the outer vertical face of an upright insulator pin, the lower end of said bar being continued to form a U-shaped portion, the outer leg of which is directed vertically upwardly and spaced from the pole engaging portion, and adapted to engage the inner vertical face of another upright pin. 115

6. An insulator support comprising a 120

- pair of similar metallic members, with means for securing the same to the opposite sides of the pole, said members being extended vertically above the top of the pole 5 and adapted to receive between them an upright insulator pin, which is secured thereto, the lower ends of said members being extended outwardly in opposite directions from the pole and engageable with the vertical inner faces of separate upright insulator pins, and outer clamping members 10 also secured to the pole and having vertical end portions cooperating with the lower ends of the first mentioned clamping members for holding said separate insulator pins in place.
7. An insulator support comprising two pairs of metallic members, said pairs being securable to a pole for fastening three 20 upright insulator pins thereto, the inner pair of members having one of their ends extended vertically above the pole and holding between them one of said insulator pins, the lower ends of said inner pair being extended outwardly from the pole and cooperating with the upper ends of the other 25 pair of members to individually clamp between them the other two insulator pins.
8. An insulator support comprising two 30 pairs of cooperating members, said members being securable to a pole, one pair of said members being extended in opposite directions outwardly from the pole where secured thereto and engaging one side of
- separate upright insulator pins, and the other pair being extended outwardly from the pole where secured thereto and cooperating with the first mentioned pair of members to hold the separate insulator pins in position.
9. An insulator support comprising two pairs of members, both pairs being securable to a pole, one pair having their lower ends bent outwardly and upwardly and terminating in vertical clamping portions, and the other pair extending upwardly and outwardly from the pole and also terminating in vertical clamping portions, the clamping portions of the two pairs cooperating to hold between them a pair of separate upright insulator pins.
10. An insulator support for holding pairs of insulator pins in spaced relation from a pole and in spaced relation to each other, comprising a plurality of pairs of members arranged in vertical order along the pole, each member having at opposite ends clamping portions for engaging opposite vertical faces of upright insulator pins, the lower clamping portion of an upper 55 clamping member cooperating with the upper clamping portion of a lower clamping member to hold a pin in place.

In testimony, that I claim the foregoing as my own, I have hereto affixed my signature.

RALPH EARLY DUFFY.
